(57) **CLAIM**

The ornamental design for a large wheel chock, as shown and described.

DESCRIPTION

FIG. 1 is a frontal perspective view of my new design;

FIG. 2 is a top plan view thereof;

FIG. 3 is a frontal view thereof;

FIG. 4 is a rear view thereof;

FIG. 5 is a left side view thereof;

FIG. 6 is a right side view thereof; and,

FIG. 7 is a right side view thereof.

The broken lines are for environmental purposes only and form no part of the claimed design.
